MESH ATTACHING MACHINE

Application filed June 6, 1925. Serial No. 35,433.

This invention relates to the manufacture of articles of wire mesh fabric, such as ladies' hand bags, and the like, which consist of a metal frame or support, to which a piece of mesh of appropriate form is attached; more particularly, the invention involves the provision of a machine by which a piece of mesh may be attached to a frame or other similar support by means of a continuous strand of wire.

In the manufacture of articles which include link mesh fabric and a frame, as heretofore carried on, it has been customary to secure the mesh to the frame by manual operations. For instance, the links of the mesh along the line of attachment may be secured to the frame by soldering or the frame may be provided with a plurality of apertures and rings may be inserted through these apertures and the links of the piece of mesh. In another operation the frame is provided with a series of apertures and a spiral wire is threaded through a row of links in the mesh and through the apertures in such a way that each link is held in place by a convolution of the wire, which then passes through one of the apertures adjacent the link. Another method of attachment involves the use of two spiral wires, one of which is soldered or otherwise secured to the frame, and the second threaded through the links along the piece of mesh, and also through the convolutions of the wire on the frame, so that each link is held to a convolution of the wire on the frame by a convolution of the second, or attaching, wire. All of these operations are carried on manually, and are, therefore, expensive, and the rate of production is low. The attaching of the piece of mesh to the frame by means of individual links of the piece of mesh requires the utmost attention on the part of the workman, in order to secure a perfect article, because if one link is missed during the attaching operation the finished article has a hole between the frame and the piece of mesh at this point, and the article, therefore, is imperfect, and must be repaired before it can be sold. When a spiral wire is used for attachment, this repair operation is quite difficult and with any of the methods as heretofore

practiced, the manufacture of the articles is expensive, not only on account of the high labor cost, but also because of the necessity of rigid inspection of the finished product.

The present invention is directed to the provision of a machine by which a piece of mesh may be automatically attached to a frame, or other support of that character, by means of a continuous piece of wire. In a machine constructed in accordance with the principles of the invention, the frame formed with a series of apertures and a piece of mesh to be attached to it, are supported in appropriate relation, so that a row of links through which the attaching wire is to be introduced lies in registry with the apertures. A supply of wire is provided, together with suitable devices for threading the wire through the links and the apertures in registry with them. At each stage in the operation of the machine one of these devices draws wire from the supply and passes a loop of it through a link and aperture. The loop of wire is then engaged by a loop former, and the first member is retracted, leaving the loop behind. This loop is then bent to lie in registry with the next succeeding link and aperture in the series, and a second loop is formed, which passes through the second link and aperture and the loop first inserted, thus holding the inner end of this loop in position. The support on which the frame and the piece of mesh, are mounted and the tools are given a step-by-step relative movement, and at each period of rest in this movement, a loop of wire is introduced. The cycle of operations continues until each link and aperture along the frame has been entered by the wire, and the inner ends of the loops are held in place by a chain stitch effect. The wire is then cut and its loose end is secured to the frame in any appropriate manner.

The machine is entirely automatic in action, and as soon as the frame and the piece of mesh have been placed in position the machine is started and the operation continues until each of the links has been secured to the frame. The machine is then stopped, the completed bag removed, and another frame and piece of mesh placed in posi-

tion. The machine thus requires little attention on the part of the operator, and its rate of production is high.

While the principles of the invention may be utilized in various machines, I have illustrated the invention as embodied in a machine for attaching a cylindrical piece of mesh to a frame in the form of a ring, the mesh being secured along one edge of the frame. In these drawings,

Fig. 1 is a side view of the machine,

Fig. 2 is a vertical, sectional view of the support for the piece of mesh and the frame to which it is to be attached,

Fig. 3 is a transverse sectional view on the line 3—3 of Fig. 2,

Fig. 4 is a top plan view of the machine,

Fig. 5 is a horizontal, sectional view on the line 5—5 of Fig. 1,

Figs. 6 and 7 are plan views of details of the mechanism shown at different stages in the operation,

Fig. 8 is an inside view in elevation of a section of a frame and a piece of mesh showing the attaching wire in place,

Fig. 9 is an outside view of the section of the frame shown in Fig. 8,

Fig. 10 is a sectional view of a detail of the machine showing the manner in which a loop 30 of wire is introduced,

Figs. 11, 12, 13, and 15 are plan views similar to Figs. 6 and 7, showing parts of the mechanism at different stages in their operation, and

Fig. 14 is a view in elevation showing the parts of the mechanism in the position occupied in the stage illustrated in Fig. 15.

Referring now to these drawings, the machine is seen to consist of a bed plate 20, supported on legs 21, in any convenient place. Mounted on the bed plate 20, is a cylindrical support 22, in the upper end of which is a recess in which is received the frame 23. The support 22 is hollow and near its lower end is provided with a ring ratchet 24. Beneath the ratchet the support is channeled, at 25, and the lower end of the support enters a recess 26 in the top of the bed plate. A split bearing plate 27 is bolted to the face of the bed plate, enters the channel and serves to hold the support against displacement.

The piece of mesh shown in dotted lines at 28, which is to be attached to the ring frame, is of generally cylindrical shape, having one end closed, and this piece of mesh is supported in relation to the frame on a cylindrical member 29, which is split longitudinally into two parts, 30 and 31, each of which has a longitudinal tongue 32 along one edge, which overlies the edge of the other part when the two are in assembled relation. At the lower end, these members have tongues 33, which fit down within the upper edge of the ring frame 23. The piece of mesh 28 fits over the cylindrical support 29, and its upper end

hangs down within the support. The piece of mesh is kept in proper relation to the support by means of a ring 34, which is slipped over the end of the split support when the mesh is placed thereon. With this arrangement it will be observed that the sleeve-like piece of mesh may be maintained in proper relation to the frame with its marginal row of links in registry with the apertures 35 formed in the frame. When the machine has completed its operations and the piece of mesh is attached to the frame, the ring 34 is removed and then one of the members 30 or 31 is sprung inwardly to free the edge of the other. Then the two may be slipped out through the frame 23, and removed.

Mounted on one end of the base plate is a bracket 36, carrying a pin 37, on which is slipped a spool 38 of the attaching wire. This spool is forced against a fixed collar 39 on the pin by a spring 40, the other end of which bears against a removable collar 41. The spring exerts pressure on the spool so as to prevent its over-running. The wire 42 from the supply is led off between rollers 43, mounted on a pin 44 in a bracket 45, secured to a block 46 mounted on the face of the base plate. These rollers are loose on the pin 44 but are forced together by a spring 47. The wire running between them is thus frictionally held, so that it will stay taut when pulled from the supply.

Mounted in the block 46 in a suitable guide-way is the needle holder 48, in the forward end of which is detachably secured the needle 49. The rear end of the needle holder is straddled between the collars 50 by the forked end of a lever 51, pivotally mounted on a pin 52 supported in a bracket 53 at one end of the bed plate. At its lower end the lever 51 carries a roller 54, bearing against a cam 55 on the main drive shaft 56 of the machine. This shaft is supported below the bed plate in suitable bearings 57 and at one end carries a pulley 58, by which it may be driven from any convenient source of power, and at the other end, a hand wheel 59 by which the machine may be manually operated in order to set the parts for starting. The lever 51 is held with its roller against the face of the cam by a spring 60, bearing at one end against the block 46, and at the other against the lever.

Mounted on the face of the bed plate near one side thereof, is a slide 61, running in guide-ways formed in blocks 62 bolted to the bed of the machine. At its rear end the slide carries an adjusting screw 63, and this screw is engaged by the end of a lever 64, pivotally mounted on a pin 65, supported in suitable brackets 66, depending from the lower surface of the bed plate. The lower end of this lever 64 carries a roller 67, which bears against a cam 68 on the main shaft 56. The slide 61 is moved to the rear, as shown in

Fig. 4, by a spring 69, secured at one end to a pin 70 in the block 62, and at the other end to a pin 71 carried by the slide. The slide carries at its forward end a pawl 72 held by a leaf spring 73 so as to engage the teeth of the ratchet 24 carried by the support, and as the slide is moved in one direction by the lever 64, the pawl engages the teeth of the ratchet and causes the support to be advanced by one step. The spring 69 returns the slide in its retractile movement, and the pawl 72 slips over the teeth of the ratchet in a position to engage the next tooth. Mounted on the bed plate in a suitable block 74, is a stop pawl 75, spring pressed so as to engage the teeth of the ratchet 24, this pawl being so arranged as to prevent any return movement of the ratchet as the pawl slides over the teeth thereof.

Mounted on an upright rod 76, extending through an aperture in the bed plate and up through the cylindrical support 22, is a collar 77, which may be secured in different positions of adjustment by means of set screws 78. This collar carries a hook-like member 79, which assists in forming the loops of wire. The needle 49 and the member 79 constitute loop-forming mechanism. The rod 76 rests at its lower end on an adjustment screw 80 in the end of a rocking lever 81, pivotally mounted on a pin 82, supported in a bracket 83, depending from the bed plate. Beyond the pivot pin, the lever 81 carries a roller 84, bearing against a cam 85 on the main cam shaft. A spring 86 encircles the rod 76 and, at its upper end, bears against an apertured block 87 which is secured to the bed plate and through which the rod passes. At its lower end, the spring bears against a collar 88, secured to the rod. This spring serves to hold the rod against the end of the adjustment screw 80. Extending from the collar, and formed integrally with it, is a lever 89, the end of which bears against an adjustment screw 90, on a slide 91, mounted in a bracket 92, depending from the bed plate of the machine.

The slide carries a roller 93 bearing against the cam 94, mounted on the main drive shaft 56, and the end of the lever 89 is held against the head of the adjustment screw by the spring 95, attached at one end to the end of the lever and at the other to the bracket 92. The arrangement is such that as the cam 94 rotates, the lever 89 and the rod 76 are rocked at the appropriate instant. The face of the lever against which the adjustment screw bears, is sufficiently broad so that the two are in contact, regardless of whether the rod is moved to the upper or lower position under the influence of the rocking lever 81.

Also mounted within the cylindrical support 22 is an upright lever 96, pivoted on a pin 97, mounted in the frame 23. A leaf spring 99, secured to the bed plate of the ma-

chine, bears against the lever beyond the pivotal point, and forces a roller 100, carried by the lower end of the arm against the face of a cam 101, on the main drive shaft. The upper end of the lever 96 carries a block or anvil 102, which lies in the plane of the series of apertures in the frame 23, when the latter is in place in its support. Under the influence of the cam 101, this anvil is moved toward and away from the frame at the appropriate instant. The anvil lies directly in front of the needle 49 in the plane thereof.

In the operation of the machine, the frame 23 is first placed in position in the upper end of the support, then the bag or sleeve of mesh to be attached to it, is placed over the split supporting cylinder 29 and held in place by the ring 34. In mounting the piece of mesh in position, it is placed with the row of links which are to be attached to the frame, in registry with the apertures therein. The wire 42 is now drawn from the supply, passed between the friction rolls 43, and then led through the eye 103 formed in the end of the needle. As shown best in Fig. 10, the needle is cut-away on its under surface at 104, to the rear of the needle eye. The wire is drawn through the eye so as to provide a loose end of the desired length, and then the machine set in operation.

The stages of the operation are illustrated in the several figures from Fig. 6 onward. In the first stage in the operation, as shown in Fig. 6, the needle is in retracted position, and the wire passes through the needle eye. The needle now advances through a link 105 and the aperture 106 in registry with it, the anvil being in retracted position. At this time the loop former 79 lies in the plane of the apertures, but is at one side of the aperture through which the loop of wire is to be passed. When the needle is in its extreme forward position as shown in Fig. 7, the loop former 79 moves toward it, and its point enters the recess 104, formed in the under side of the needle, passing between the needle and the wire, and thus entering the loop. As the needle returns to its outermost position, as shown in Fig. 11, the loop 107, which has been introduced through the link and the aperture 106 in registry with it, will be held by the loop former.

The next operation is the movement of the support by one step, as shown in Fig. 12, during which movement the loop held by the former is bent slightly as indicated at 108, the end of the loop lying toward the next adjacent aperture in the series. When the support with the frame and the piece of mesh on it, has come to rest, the loop former 79 is retracted so as to free the loop 108, as shown in Fig. 13, and as soon as the loop former is clear of the loop, the rod on which it is carried is moved upwardly so that the former occupies the position illustrated in Fig. 14,

where it will be seen that the former lies above the plane of the aperture through which the loop has been inserted. The lever 96 is now rocked so as to carry the anvil 102 forwardly, and the anvil forces the loop 108, into the position shown in Fig. 15, where the end of the loop is in registry with the next aperture and link in the series. When the wire has been bent against the frame into this position of registry, the anvil is retracted and the cycle of operations is repeated. The needle moves forward, so as to carry a loop of wire through the next link and aperture, and in so doing, the loop enters the loop previously mentioned, which lies against the inner face of the frame in registry with this link and aperture. Thus the second loop not only passes through the link and the frame, but also through the loop first formed, locking this loop in position. As soon as the second loop has been formed, the loop former engages it and holds it while the needle has been retracted, then the frame support advances one step, the second loop is cleared and bent by the anvil into registry with the third link and aperture. This series of operations is repeated throughout the entire frame, and thus the frame and piece of mesh are united by loops of wire which are held in place by a chain stitch effect.

In Figs. 8 and 9 there is illustrated more clearly the manner in which the mesh is attached to the frame, and it will be seen in Fig. 9, which is an outside view of the frame 35 with the piece of mesh in place, that there is visible a length of wire 109 which extends between adjacent links in the row. Between these adjacent visible lengths of wire the wire forms a loop 110, which passes through a link and the aperture in registry with it, and is then bent into registry with the next succeeding link and aperture. Each loop after the first not only passes through a link and aperture, but also through the previously 50 formed loop, so that the loops which serve to attach the links to the frame are held together by a chain stitch. Since only short lengths of the wire are visible on the outside of the frame, the loops being concealed within, this attaching wire does not detract from the appearance of the finished article. Furthermore, by this method of attachment, the frame and the piece of mesh are securely held together, and the operation can be carried 55 on rapidly and at a low cost.

In the machine as illustrated, all the working parts are driven from the main drive shaft in proper timed relation, and a complete cycle of operations takes place for each 60 revolution of the drive shaft. Accordingly, each such revolution corresponds to the insertion of a loop of wire through the mesh and the frame aperture in registry with it, and consequently the attachment of a piece of mesh to a frame takes a short time and each 65

link of the mesh is secured to the frame so that the bags completed on this machine are perfect, except in the event that the wire breaks. When this occurs the needle is again threaded and the operation started so that the first loop will enter the last loop previously made. The loose ends of wire may then be twisted together or soldered and inserted through one of the apertures, and the attachment completed. Whenever a bag has been 70 finished, it may be quickly removed and the new frame and piece of mesh placed in proper position in the machine. These operations are simple and consume little time, so that the machine may be operated with a large 75 output.

While I have illustrated a machine embodying the principles of the invention which is intended for use in the attachment of pieces of mesh to frames in the form of a ring, it will be apparent that the same method of attachment may be employed in attaching mesh to frames or other similar articles of an irregular outline; as, for instance, hand bag frames of a general U-shape. Regardless of the type 80 of frame to which the mesh is attached, the same principles of operation are involved, namely, the frame and the piece of mesh to be attached to it, are given a step-by-step movement relative to appropriate tools, and during the periods of rest in the step-by-step 85 relative movement of the frame and the tools, the tools operate to form a loop of wire, insert it through a link and the aperture in registry therewith, and also through the loop of wire 90 previously formed.

I claim:

1. A machine for attaching link mesh fabric to a frame or other similar article having a series of apertures formed therein, which comprises the combination of a support for the frame and the piece of mesh to be attached thereto, the mesh being held with a row of links in registry with the apertures in the frame, means for holding a supply of wire, power-driven tools for drawing wire from the supply and inserting a loop of wire through each link and the aperture in registry therewith successively, means independent of the tools for bending the loop so inserted to a position in which it will be entered by the loop inserted through the next succeeding link and aperture, the said bending means disengaging the loop prior to the next loop-inserting operation of the said tools, and means for giving the support a step-by-step relative movement to said tools and said means, the tools and said means being actuated during the periods of rest of the said step-by-step relative movement.

2. A machine for attaching link mesh fabric to a frame or other similar article having a series of apertures formed therein, which comprises the combination of a support for the frame and the piece of mesh to 130

be attached thereto, the mesh being held with a row of links in registry with the apertures in the frame, means for giving the support a step-by-step movement of rotation, means for holding a supply of wire, a needle movable relatively to the support for drawing wire from the supply and inserting a loop of it through each link and the aperture in registry with it in succession, a former for holding the loop so inserted while the needle is being retracted, and an anvil operable to bend the loop so inserted to a position in which it will be entered by the loop inserted through the next succeeding link and aperture in the series.

3. A machine for attaching link mesh fabric to a frame or other similar article having a series of apertures formed therein, which comprises the combination of a support for the frame and the piece of mesh to be attached thereto, the mesh being held with a row of links in registry with the apertures in the frame, means for giving the support a step-by-step movement, means for holding a supply of wire, a moving needle operable to draw wire from the supply and insert a loop of the wire through each link and the aperture in registry with it in succession, a former movable to disengage the loop so inserted from the needle and to hold this loop during the retractile movement of the needle, and an anvil operable to bend the loop so inserted to a position in registry with the next succeeding link and aperture whereby it will be entered by the loop next formed and inserted, the needle, the former, and the anvil being operable to perform their functions during the periods of rest of the step-by-step movement of the support.

4. A machine for attaching link mesh fabric to a frame or other similar article having a series of apertures formed therein, which comprises the combination of a rotary support for the frame, and means movable therewith for supporting a piece of mesh in relation to the frame, the mesh being held with a row of links in registry with the apertures in the frame, power driven devices for giving the support a step-by-step movement, means for holding a supply of wire, a reciprocating needle movable toward and away from the support and operable upon its forward movement to draw wire from the supply and insert a loop of the wire through a link and the aperture in registry with it, a former disposed within the support and movable to disengage the inserted loop of wire from the needle upon the retractile movement of the latter, and an anvil disposed within the support and movable toward and away from the frame to bend and insert a loop to a position in registry with the next succeeding link and aperture, whereby the loop of wire inserted therethrough will pass through the loop so bent.

5. A machine for attaching link mesh fabric to a frame or other similar article having a series of apertures formed therein, which comprises the combination of a support for the frame and means associated therewith for supporting the piece of mesh to be attached thereto in relation to the frame, the mesh being held with a row of links in registry with the apertures in the frame, means for holding a supply of wire, a reciprocating needle movable toward and away from the frame, and in its forward movement operable to draw wire from the supply and insert a loop of wire through a link and the aperture in registry with it, a former disposed within the support and operable to enter the loop so inserted and hold the latter upon the retractile movement of the needle, an anvil disposed within the support and movable toward and away from the latter, this anvil being operable upon the disengagement of the loop from the former to bend the loop toward the frame to a position in registry with the link and aperture next succeeding in the series, and power driven devices for giving the support a step-by-step movement relative to the needle, the former, and the anvil, and for actuating these elements in the periods of rest of the step-by-step relative movement.

6. A machine for attaching link mesh fabric to a frame or other similar article having a series of apertures formed therein, which comprises the combination of a support for the frame, means connected therewith for supporting a piece of mesh to be attached to the frame in relation thereto, the mesh being held with a row of links in registry with the apertures in the frame, means for holding a supply of wire, a reciprocating needle movable relatively to the support and on its forward movement operable to draw wire from the supply and insert a loop of the wire through a link and the aperture in registry with it, a former disposed adjacent the support and movable into and out of the plane of the series of apertures, this member being oscillated when in effective position to enter the loop inserted by the needle and disengage the loop from the needle upon the retractile movement of the latter, the former being thereupon actuated to release the said loop and move out of the plane thereof, an anvil movable toward and away from the frame and operable to engage the loop so released and bend it into a position in registry with the link and aperture next succeeding, the anvil being actuated when the former has been moved out of the plane of the apertures, and power-driven devices for giving the frame a step-by-step movement relative to the needle, the former, and the anvil, and for actuating these elements during the periods of rest of this step-by-step movement.

7. In a machine for attaching link mesh

5 fabric to a frame or other similar article having a series of apertures formed therein, the combination of means for holding a supply of wire, a needle for forming loops of
10 5 wire drawn from the supply and inserting these loops through the apertures in the frame, a former operable to disengage each loop so inserted from said needle, and an anvil operable to bend the disengaged loop
15 10 to a position in registry with the next succeeding aperture in the frame.

8. In a machine for attaching link mesh fabric to a frame or other similar article having a series of apertures formed therein, the combination of means for holding a supply of wire, a needle reciprocating in a plane and operable upon its forward movement to form a loop of wire drawn from the supply and insert this loop through an aperture in
15 20 the frame, a former movable into and out of the plane of reciprocation of the needle, and movable in that plane to enter the loop so inserted and disengage it from the needle upon the retractile movement of the latter,
25 25 this former then releasing the loop and moving out of said plane of reciprocation, and an anvil reciprocating in the same plane as the needle and operable to bend the loop into registry with the next succeeding aperture to
30 be entered.

9. In a machine for attaching link mesh fabric to a frame or other similar article having a series of apertures formed therein, the combination of a hollow support for the frame, means carried by the support for holding a piece of mesh to be attached to the frame with a row of links of the mesh in registry with the apertures in the frame, means for holding a supply of wire, a reciprocating slide carrying a needle through the eye of which the wire is led, the slide being operable to pass the needle through a link and the aperture in registry therewith carrying the wire with it, an oscillatory rod carrying a
35 40 45 former adapted to enter the loop of wire introduced through a link and aperture by the needle and to hold the loop as the needle is retracted, this rod being also reciprocable in a vertical direction to carry the former into and out of the plane in which the needle moves, a rocking lever carrying an anvil adapted to engage the loop upon its release by the former and to bend this loop into
50 55 60 registry with the next succeeding link and aperture in the series, and power-driven devices for giving the support a step-by-step movement of rotation and for operating the slide, the rod, and the lever to cause the needle, the former, and the anvil to perform their functions in timed relation to the movements of the support.

10. In a machine for attaching link mesh fabric to a frame or other similar article having a series of apertures formed therein, the combination of means for holding a supply of wire,
65

a reciprocating needle for drawing wire from the supply and for inserting loops of the wire through the apertures in the frame and the links of the piece of mesh, a former operable to enter the loop inserted by the needle and hold the same during the retractile movement of the needle, the said former being actuated to release the loop prior to the next inserting movement of said needle, and means operating upon the loop upon its release by the former for bending the loop into registry with the next succeeding link and aperture in the series.

11. In a machine for attaching link mesh fabric to a frame or other similar article having a series of apertures formed therein, the combination of a support for the frame and the piece of mesh to be attached thereto, the mesh being held with a row of links in registry with the apertures in the frame, means for holding a supply of wire, a reciprocating needle through which the wire is threaded and which is operable to introduce the wire in the form of a loop through a link and the aperture in registry therewith, a former on the opposite side of the frame from the needle movable to enter the loop of wire formed by the needle and hold the latter during the retractile movement of the needle, the said former being actuated to release the loop prior to the next movement of the needle to insert a loop through the mesh, and means adjacent the former and operating in timed relation thereto to engage the loop upon its release by the former and bend the loop into registry with the next succeeding link and aperture in the series.

12. In a machine for attaching link mesh fabric to a frame or other similar article having a series of apertures formed therein, the combination of a support for the frame and the piece of mesh to be attached thereto, the mesh being held with a row of links in registry with the apertures in the support, means for holding a supply of wire, a needle reciprocating lengthwise and operable upon its forward movement to draw wire from the supply and insert a loop of this wire through a link and the aperture in registry therewith, a former movable into and out of the plane of reciprocation of the needle and movable in that plane to enter the loop of wire inserted by the needle and hold this loop upon the retractile movement of the needle, the said former releasing the loop prior to the next advancing movement of the needle, and reciprocating means engaging the loop upon its release by the former and operable to bend the loop out of the path of reciprocation of the needle and toward the next aperture in the frame to be entered by the needle.

13. In a machine for attaching link mesh fabric to a frame or other similar article having a series of apertures formed therein, the combination of a support for the frame and

the piece of mesh to be attached thereto, the mesh being held with its links in registry with the apertures in the frame, means for holding a supply of wire, a reciprocating needle 5 operable to draw wire from the supply and insert loops of the wire through a link and the aperture in registry therewith, means for engaging each loop so inserted and bending this loop against the face of the article into 10 registry with the next succeeding aperture, and power-driven devices for giving the support and the needle a step-by-step relative movement and for operating the needle and the said means in the periods of rest of this 15 movement.

14. In a machine for attaching link mesh fabric to a frame or other similar article having a series of apertures therein, the combination of a needle for forming loops of wire 20 drawn from a supply and inserting these loops through the apertures in the frame, a former operable to disengage each loop so inserted from the needle and thereafter releasing said loop, and means engaging the 25 loop after it has been freed by the former for bending the loop to a position in registry with the next succeeding aperture in the frame.

15. A machine for attaching link mesh fabric to a frame or other similar article having a series of apertures formed therein, which comprises the combination of a support for the frame and the piece of mesh to be attached thereto, the mesh being held 30 with a row of links in registry with the apertures in the frame, means for holding a supply of wire, reciprocating means for drawing wire from the supply and forming a loop passing through a link, the aperture in registry therewith, and the loop inserted through 35 the next preceding ring and aperture in the series, means independent of said loop-forming means and operable after said loop has been completed thereby and freed therefrom 40 to engage said loop and bend it to a position in registry with the next succeeding link and aperture in the series, and means for giving the support and the said link forming and bending means a step-by-step relative movement. 45

16. A machine for attaching link mesh fabric to a frame or other similar article having a series of apertures formed therein, which comprises the combination of a support for the frame and the piece of mesh to be attached thereto, the mesh being held with 50 a row of links in registry with the apertures in the frame, means for holding a supply of wire, mechanism operable to draw wire from the supply and form a loop of wire which 55 extends through a link, the aperture in registry therewith and the loop inserted through the next preceding link and aperture in the series, said mechanism including a reciprocating element, means independent of the said 60

mechanism and operable after the loop has been freed thereby for engaging the loop and bending it into registry with the next succeeding link and aperture in the series, and means for giving the support and said mechanism and means a step by step relative movement, the insertion of the loop being carried on by said mechanism during the periods of rest in the step-by-step movement. 70

17. A machine for attaching link mesh fabric to a frame or other similar article having a series of apertures formed therein, which comprises the combination of a support for the frame and the piece of mesh to be attached thereto, the mesh being held with a row of links in registry with the apertures in the frame, means for holding a supply of wire, cooperating tools for drawing wire from the supply and forming a loop of wire inserted through a link, the aperture in registry therewith, and the loop inserted through the next preceding link and aperture in the series, means independent of the tools for engaging the said loop after it has been inserted by said tools and freed therefrom, and bending the said loop into registry with the next succeeding link and aperture in the series, and means for giving the support and the loop-inserting and bending means a 80 step-by-step relative movement. 85

18. In a machine for attaching link mesh fabric to a frame or other similar article having a series of apertures therein, the combination of a support for the frame and the piece of mesh to be attached thereto, the said piece of mesh being held with a row of links in registry with the apertures in the frame, means for holding a supply of wire, means for drawing wire from the supply and inserting a loop of the wire through a link and the aperture in registry therewith, means independent of the loop inserting means for bending this loop into registry with the next succeeding link and aperture, the loop being released by the inserting means prior to the operation of the bending means, and power-driven devices for moving the support with a step-by-step movement and for actuating the said means in timed relation thereto. 100

In testimony whereof I affix my signature. 105
